UNITED STATES PATENT OFFICE.

WILLIAM HENRY BELL, OF SAN FRANCISCO, CALIFORNIA.

GLOVE-FASTENER.

SPECIFICATION forming part of Letters Patent No. 466,819, dated January 5, 1892.

Application filed May 3, 1889. Serial No. 309,480½. (No model.)

To all whom it may concern:

Be it known that I, WILLIAM HENRY BELL, of San Francisco city and county, State of California, have invented a Glove-Fastener; and 5 I do hereby declare the following description and accompanying drawings are sufficient to enable any person skilled in the art or science to which it most nearly appertains to make and use my said invention without further 10 invention or experiment.

The object of my invention is to construct a fastener for gloves, shoes, &c., in such a manner that by one operation of the wearer a uniformity of pressure is (by slight effort) 15 brought to bear on both flaps of the glove, (be they wide or narrow,) whereby both flaps may be quickly drawn together and securely held in place. I attain these objects by the cord-and-string device and spring-holder illustrated in the accompanying drawings, in 20 which—

Figure 1 is a perspective view of the cord-and-string device applied to a glove as it appears when loose or open; Fig. 2, a view showing the two flaps of the glove drawn together by the string D, with the cord A held in place by the spring-holder G; Fig. 3, a face view of the cord-and-string device and spring-holder applied to a wide glove-band; Fig. 4, an enlarged perspective view of the single-wire two-post spring-holder G.

Similar letters refer to similar parts throughout the views.

The annular guide B, having the cord A attached, and the string D, one end C of which is fastened to the inside of the overlapp of the glove. The remaining end F, after being passed through the annular guide B and through the hole E in the overlapp of the 35 glove, is fastened to the outside of the under flap. It will be seen by referring to Figs. 1 and 2 that with this device the flaps of the glove may be drawn apart to the extent of the full length of the string D, and when the flaps 40 are drawn together the string D is doubled, allowing the holder to be placed much nearer the glove-opening than was heretofore the custom.

The holder G is a two-post spring-holder 45 made of one piece of wire bent to the shape of an inverted figure 8. The two ends of the

wire being bent at right angles constitute the two posts T and S, which are fitted to the base-plate H and riveted to the under flap of the glove, imparting to the two loops P and L 55 spring-power for pressure, so that if a cord A were tightly drawn under the loops P and L, round the post T, between the two posts T and S, into the receiving-loop L a springing action would be produced, tending to grip the 60 cord A between the two posts T and S, the base-plate H, and the two loops P and L at their connection. (See Fig. 4.)

To obtain sufficient spring-power to securely retain the cord A in the receiving-loop L, the 65 two posts T and S, formed from the ends of one piece of wire, are indispensable. They are also necessary to prevent the holder from shifting and turning. This spring-power for pressure is not obtained in an ordinary one-post holder or in a wire-holder made of more than one piece of wire; but being made of one piece of wire with the ends for posts the entire length of the wire from the post T to the post S is a spring for pressure, having a greater 70 degree of elasticity at the point where the two loops P and L connect.

The annular guide B, with the cord A attached, may be arranged for one or more strings D D and made of wire, if preferable, 75 (with or without spring,) as shown in Fig. 3.

For closing and fastening the glove at the wrist it is necessary to draw the cord A tightly round the post T, under the loop P, and between the two posts T and S into the receiv- 85 ing-loop L. (See Figs. 2 and 4.) For opening the glove it is necessary to release the cord A from the holder G.

Having thus described my invention, what I claim as new, and desire to secure by Letters 90 Patent, is—

The glove-fastener consisting of the single-wire two-post spring-holder G, bent, as described, to grip and retain a cord A within itself, in combination with the annular guide 95 B and string D, substantially as herein described and shown.

WILLIAM HENRY BELL.
